RUDOLF EICKEMEYER, OF YONKERS, NEW YORK.**

Letters Patent No. 91,729, dated June 22, 1869.

IMPROVEMENT IN FELTING-MACHINES.

The Schedule referred to in these Letters Patent and making part of the same.

To all whom it may concern:

Be it known that I, RUDOLF EICKEMEYER, of Yonkers, in the county of Westchester, and State of New York, have invented certain new and useful Improvements in Machinery for Felting Felt Cloths; and I do hereby declare that the following is a full and correct description thereof, reference being had to the accompanying drawings, forming a part of this specification, and to the letters of reference thereon.

This invention relates to jiggering-machines, in which the material is fed upon a carrying-cloth between a flat-surfaced jigger and a platen.

In some of the jiggering-machines of this class, the jigger has a continuous action upon the fabric, and the carrying-cloth or conductor has a slow continuous motion, but such machines do not admit of applying the jiggering-surface to the fabric under heavy pressure, and consequently are only suitable for hardening the fabric, preparatory to the subsequent operation of the fulling-mill. In other machines of this class, the jiggering-apparatus is applied to the fabric, while the carrying-cloth is at rest, and the jiggering proceeded with for a period of time regulated by the machinery when it ceases, and the fabric is moved forward about the distance of the width of the jiggering-apparatus, and the jiggering again proceeded with, these operations being repeated, to felt a continuous fabric; but such machines necessarily produce unevenly-felted fabrics, because the entire surface of the fabric is not subjected to the action of all parts of the jiggering-surface, and because the speed of the jigger and the heat and moisture may vary upon the successive squares of the fabric successively acted upon by the jigger.

The object of this invention is to remedy the defects last mentioned, and to produce evenly-felted fabrics, progressively felted by the operation of the machine. This is accomplished by combining with the mechanism that regulates the period of time during which the jigger acts upon the fabric to be felted, a mechanism which moves the fabric forward with the carrying-cloth a short distance compared with the width of the jiggering-surfaces, whenever the fabric is released from the action of the jiggering-surface, and then remains at rest until the jiggering-surface has repeated its action upon the fabric and retreated therefrom, these operations being repeated until the desired length of fabric is felted.

By this mode of operation, all parts of the jiggering-surface are applied to all parts of the fabric passing through the machine during regular and uniform periods of time, and the fabric thereby becomes uniformly felted.

This invention further consists in combining, with the felting-platen, carrying-cloth, and flat-surfaced jigger, a system of rotating cams and weighted levers

connected with the jigger, substantially as hereinafter described, whereby the jiggering-surface is pressed upon the fabric with a determinate pressure during regular periods of time, and released from the fabric at regular intervals, in order to permit of the intermittent progressive movement of the carrying-cloth.

Figure 1 of the drawings represents a longitudinal section of the machine;

Figure 2, an end view; and

Figure 3, a plan view of the same.

The side frames a a' of the machine are framed together by the cross-braces a^2 a^3 a^4 .

The platen b is secured to the side frames by the screws b^1 b^2 b^3 b^4 .

The carrying-cloth c is an endless apron or conductor, of linen, canvas, or other suitable material for a hardening-cloth, extended over the drums d d^1 d^2 d^3 , and moved intermittently at regular intervals, a short distance, compared with the width of the platen, in the direction indicated by the arrows, by a pawl, e , and ratchet e' , the latter attached to the shaft of the drum d .

The flat jigger-plate f forms the top plate of the steam-box f^1 , and is perforated with fine holes to permit steam to pass to the fabric to be felted.

The steam-box f^1 has suitable induction and education-pipes f^2 f^3 , (shown broken off,) which should be connected, by flexible connecting-pipes, with a source of supply of steam and a waste-water receptacle. This steam-box, with its flat rubbing-surface, is placed beneath the platen, under that portion of the carrying-cloth in contact therewith, and receives a very short and exceedingly rapid reciprocating motion from the crank-shaft g , which may be driven as usual by a rapid belt from a separate counter-shaft overhead, running upon the driving-pulley g^1 , and is connected with the steam-box f^1 , by two connecting-rods, g^2 g^3 .

At each side of the jiggering steam-box, are guides g^4 g^5 , which do not interfere with its being moved toward and from the felting-cylinder.

The steam-box and its jiggering-surface are moved up and down, and held against the hardening-cloth and felting-cylinder with a yielding pressure, by mechanism, as follows, viz:

The steam-box is supported by four rocking columns, two of which, h h' , are connected by joints to lugs or projections from the lower part of a sliding plate, i , which slides up and down within the frame upon the side frame a' , the upper part of the sliding plate i having a guide-bar, i^1 , projecting upward from it, which slides in a recess in the end of the cross-brace a' , the lower part of the sliding plate being guided by the cam-shaft, which passes through a slot made in the middle of the lower part of the plate for that purpose; and the other two columns, one only, h^3 , shown in the drawings, are similarly connected to an oppo-

*Assigned to John T. Young.

site sliding plate, i^2 , which slides up and down upon the opposite side frame, in the same manner as the sliding plate i .

The two opposite sliding plates i and i^2 are exactly alike, facing each other on opposite sides of the machine within the side frames, and are each independently moved up and down at the same time, by means of the cams k^1 k^2 , fast to the cam-shaft k , operating through two systems of weights and levers, one system for each sliding plate.

The two systems of weighted levers being alike, a description of one only will be given, that which is in connection with the cam k^1 and the sliding plate i .

This system of levers consists of a lever, m , pivoted upon the cross-shaft m^1 , and extending horizontally, the cam k^1 being provided at the ends with an anti-friction roller, m^2 , which runs on the cam k^2 .

The lever m is linked, by a short link, m^3 , to the fulcrum-point of a lever, p , immediately above it, which lever is connected to the sliding plate i at one end, and is loaded with weights p^1 at the other end.

The arrangements and proportions of the levers being as shown in the drawings, the cam lifts the sliding plate and its end of the steam-box, by lifting the weighted lever p .

When the cam turns to lower the sliding plate, the weighted lever p rests on the cross-shaft m , close by the weights, thereby relieving the sliding plate and steam-box from the upward pressure due to the weights, and permitting the steam-box to be lowered sufficiently to allow the felting-cylinder to be moved.

The rotating cam-shaft k is driven by a train of cog-wheels from the driving-shaft q , upon which are the fast and loose pulleys q^1 q^2 , as follows, viz: a pinion, r , fast to the driving-shaft q , gears into a spur-wheel, r^1 , fast to the intermediate rotating shaft r^2 , which also carries a pinion, r^3 , which gears into the spur-wheel r^4 , fast to the cam-shaft k .

The exact proportions of these wheels are not material, as they are merely used to reduce the speed, and increase the power from a light driving-belt.

The pawl e , which moves the carrying-cloth, is actuated by the lever s , to which it is connected, the lever being moved the proper distance by a wiper, in the form of a set-screw, t , screwed into the cam-shaft k .

The fabric prepared for felting, is continuously supplied to the carrying-cloth, which is moved forward by the pawl and ratchet, a short distance compared with the width of the platen and jiggering-surfaces, between which it passes, when the jigger moves away from the platen, to permit of the forward movement of the fabric. The jigger is then brought up against the fabric by the rotating cams operating through the system of weighted levers, and their connections with

the jigger, and operates upon the fabric during a regular period of time, determined by the length of the concentric surfaces of the cams, and then released from the fabric, to permit the cloth to be again moved forward a short distance, when it repeats its operation upon nearly the whole surface it has just before acted upon, thus bringing all parts of the jigger-surface in action upon all parts of the surface of the cloth to be felted.

This mode of operation involves the release of the fabric from the action of the jigger, a number of times during the operation of felting any given part of it, thus giving the fabric a better opportunity to shrink during the process of felting, than if the pressure of the jigger were continued during the whole process of felting a given square of the fabric.

The surfaces of the jigger and platen should be slightly grooved or scored, to lay hold of the fabric and carrying-cloth, and, if desired, a covering-cloth may be fed with the fabric beneath the platen.

It is better to use endless carrying-cloths, but it is obvious that carrying-cloths of sufficient length, that are not endless, may be used, by drawing them forward from a roller, in a manner well known to those using machines for preparing bats and for felting.

I claim as of my invention and improvement in machinery for felting felt cloths—

1. In jiggering-machines, wherein the fabric is carried by a carrying-cloth or conductor, between a platen and a flat-surfaced jigger, which operates upon the fabric during uniform periods of time, regulated by the machine, and is then released from it, I claim giving the carrying-cloth an intermittent progressive motion for a short distance at a time, as compared with the width of the jiggering-surface, by mechanism combined with the mechanism for regulating the periods of action of the jigger, substantially as described, so that the jigger progressively repeats its action upon portions of the fabric previously acted upon, in order to insure regular and uniform felting of the fabric, substantially as described.

2. In combination with the platen, carrying-cloth, and flat-surfaced jigger, a system of rotating cams and weighted levers, connected with the jigger, substantially as hereinbefore described, whereby the jiggering-surface is pressed upon the fabric with a determinate pressure during regular periods of time, and released from the fabric at regular intervals, in order to permit of the intermittent progressive movement of the carrying-cloth.

R. EICKEMEYER.
